CONVERSION OF HYDROCARBONS

Charles E. Jahnig, Red Bank, Harvey E. W. Burnside, Rumson, and James W. Brown, Elizabeth, N. J., assignors to Standard Oil Development Company, a corporation of Delaware

Application June 2, 1951, Serial No. 229,584

6 Claims. (Cl. 202—14)

This invention relates to a process for treating hydrocarbons and more particularly relates to the conversion of heavy residual petroleum oil to produce lower boiling hydrocarbons.

The petroleum oil residuum or residual oil which is to be converted according to the present process is a high boiling hydrocarbon oil which cannot be vaporized at ordinary pressures without cracking the high boiling constituents. At present relatively large volumes of reduced crude or heavy bottoms are available because lower grade crude oil feedstocks are being processed which leave more residue and because there is a larger demand for motor fuel such as gasoline and other petroleum oil products such as heating oil which means processing more crude oil to leave more residue.

It is known in the prior art to crack or coke heavy residual oils in the presence of finely divided inert solid particles maintained as a fluidized bed. Visbreaking is a short time cracking operation in which the purpose is to make an additional amount of gas oil feedstock and not much gasoline. In visbreaking, about 5 to 15% gasoline is produced when the temperature is at about 800° to 950° F. Higher temperatures are inoperable due to coking in the heater coil. In coking, the temperature can be much higher and the cracking more drastic. In coking at high severity, about 5-50% gasoline is made which has a higher octane number than the gasoline produced when visbreaking. During coking the final products are gasoline, some gas oil, gas and coke. Unlike visbreaking, the products from coking are withdrawn as vapors and solids rather than primarily as a liquid. The present invention can be used for high temperature and low temperature cracking of residual oils.

According to the present invention heat is supplied to a dense fluidized bed of particles in a coking bed by indirect heat transfer to the solid particles. The use of indirect heat exchange is important in supplying heat to a fluid coking bed because the coking may be carried out at a relatively high pressure while the combustion supplying the heat for the particles is carried out at low pressure, substantially atmospheric, and therefore requires little air compression. Efforts to develop heat exchange inside the coke bed have met with considerable mechanical or construction difficulties due to thermal expansion and strength of material problems especially around the relatively high temperatures of 1100° F. and above, and relatively high pressures.

According to the present invention the coke or other particles from the coking bed are circulated through U-bend transfer lines which hang from the bottom of the coking vessel. Heat is supplied to the U-shaped transfer lines in a plurality of ways.

In one form of the present invention the U-bend heat transfer lines are arranged in a fired furnace.

In another form of the invention the U-bend heat transfer tubes are arranged in a heating vessel packed with inert or ceramic spheres or the like which may contain a

2

combustion catalyst and heat is supplied to such spheres by burning a fuel in contact therewith.

In another form of the invention the U-bend heat transfer tubes are arranged in a vessel containing a fluidized bed of finely divided inert solids. The heated solids are removed from the vessel, heated outside the vessel with fuel gas and air and the heated particles then returned to the fluidized heated bed to supply heat to the U-shaped heat transfer tubes. A combustion catalyst such as an oxide or oxides of chromium, iron, etc. may be incorporated with the heat transfer solid.

In the drawings:

Fig. 1 represents one form of apparatus for carrying out the process of the present invention in which the U-bend heat transfer tubes depending from the bottom of the coking vessel are arranged in a fired furnace and the heat transfer tubes are heated by radiant and convection heat in the fired furnace;

Fig. 2 represents another form of apparatus in which the U-shaped heat transfer tubes depending from the coking vessel are arranged in a heating vessel provided with inert or ceramic spheres which are packed around the tubes and hot combustion gases are used for supplying the heat to the ceramic spheres and the heat transfer tubes; and

Fig. 3 represents another form of apparatus in which the depending heat transfer tubes arranged below the coking vessel are submerged in a fluidized bed of inert solids which are removed from the fluid bed, heated by burning a fuel gas in the presence of the removed solids and the heated inert solids are then returned to the fluidized bed for supplying heat to the heat transfer tubes. In some cases it may be preferable to heat the circulating solids by contacting with hot flue gas from a separate burner.

Referring now to Fig. 1 of the drawings, the reference character 10 designates a line through which residual hydrocarbon oil to be coked is pumped by pump 12. The residual oil may comprise atmospheric or vacuum residuum petroleum oil, reduced crude oil, tar, pitch, heavy cycle oil, clarified oil from catalytic cracking, the clarified oil being a high boiling aromatic fraction. The oil is heated to a temperature of about 400°-950° F., preferably above 600° F. by being passed through the coil 14 in furnace 16 and the heated oil is then passed through line 18 into or onto a fluidized solids bed 22 arranged in coking vessel 24 and maintained at a temperature of about 800° to 1350° F. Line 26 is provided for injecting steam into the heated feed oil passing through line 18. While only one inlet line 18 is used as shown in the drawing for supplying the heated residual oil to the coking bed, it is preferred to introduce the heated oil at a number of places into the coking bed, especially where the coking vessel is a large piece of equipment. Also, sprays or nozzles may be used at the outlet end of the line or lines 18.

The fluidized coking bed 22 has a level indicated at 28 above which is a dilute phase 32 where the upflowing gasiform material contains only a small amount of entrained solid particles. The gasiform material is passed through a gas-solids separating device such as a cyclone separator 34 arranged at the top of coking vessel 24 and provided with a dip leg 36 for returning separated solids to the dense fluidized bed 22. Gasiform reaction products pass overhead through line 38 and may be further treated as desired to recover hydrocarbon products or fractions. The coking bed 22 is maintained in a dense fluidized highly turbulent condition by upflowing gases as will be hereinafter described in greater detail. For starting up solids forming the initial bed in the coking vessel sand, finely divided petroleum coke, pumice, kieselguhr, carbonium or other similar refractory materials may be used. During coking, more coke is formed along

with liquid and gas hydrocarbons and is removed from the bed 22. During subsequent operation the inert charge material is purged from the bed and the bed may consist entirely of coke made in the process.

Arranged below the coking vessel 24 is a furnace 42 provided with a radiant heating section 44 and a convection heating section 46. The furnace is preferably formed of a cylindrical shell provided with burners 48 arranged in concentric circles for supplying radiant heat to the radiant heating section. The furnace is fired from the bottom by burners 48 and combustion gases pass upwardly in the radiant heating section. The furnace is provided with a central refractory wall 52 which is preferably circular in cross section and which is shorter in height than the height of the furnace to provide a passageway for the hot combustion gases from the radiant heating section to the convection heating section 46 formed by the refractory wall 52.

Arranged within the radiant heating section 44 of the fired furnace 42 is a plurality of U-bend heat transfer lines 54 arranged in a circle which hang from the bottom of the coking vessel 24 and have their upper ends in communication with the bottom of the coking vessel 24. With the U-bend construction, mechanical problems caused by thermal expansion are avoided. The U-bend lines 54 are shown in the drawing in a position to show the U-tube arrangement, but preferably the U-bend lines are arranged at right angles to that shown in the drawing so that one circle of tubes is formed and so that radiant heat will be supplied to both sides of the tubes.

The heat transfer tubes 54 are fired on both sides by the burners 48 which are arranged in concentric circles. Only a few of these U-shaped heat transfer tubes have been shown in the drawing but it will be understood that there are a large number of them and when the specific apparatus will be described for one form of apparatus the actual number of U-bend tubes will be given. The U-bend tubes permit dense fluidized coke or other inert particles to pass down one leg 55 and then steam is introduced into the lower portion of the other leg 58 beyond the bend as at 56 to lower the density of the mixture therein and to cause circulation of the particles through the U-bend heat transfer tube.

This same operation occurs in each of the U-bend heat transfer tubes. The fluidizing gas is preferably steam which is passed into the upflow leg 58 of the U-bend transfer tube 54 by means of manifold line 62. Steam for fluidization is preferably generated by utilizing heat from the combustion gases leaving the furnace as will be hereinafter described. The outlet end of the upflow leg of each U-bend heat transfer tube may be arranged at about the same level as the point of connection of the downcoming leg from the coking vessel 24.

Another set of heat transfer tubes is provided for the convection heating section where for simplicity, only a single U-shaped heat transfer tube 64 is shown. Here again steam or other fluidizing gas is introduced by means of line 66 into the upflow leg 68 of the U-tube to cause circulation of the solid particles in the U-tube in the convection heating section to supply heat to the solid particles from the coking bed 22.

The rate of flow of the solids in the downflow leg 55 of the U-tube heat transfer elements 54 may be between about 1 feet per second and 10 feet per second, preferably about 6 feet per second, while the rate of flow or velocity is somewhat higher on the upflow leg 58 in line with the reduction in density resulting from the addition of gas at 56. Under these conditions the heat transfer coefficients will be well above 50 B. t. u. per hour per square foot per °F. and may be between about 50 and 500 B. t. u. per hour per square foot per °F. With this method of heat transfer using the U-shaped elements and having a temperature of 850° F., for example, in the fluidized coking bed 22, the solids temperature in the coking bed 22 will be maintained within

about 10° of the desired 850° F. Also, high circulation rate through these U-shaped tubes will maintain the smallest difference of temperature between the tube wall and the coke or other solid passing through the tube.

By reducing the solids circulation rate in the U-bend transfer tubes the coke particles may be heated to a temperature substantially higher than 850° F., if desired, for the purpose of drying the coke particles or completing the reaction on the coke particles. This method of heating solids may be used in the desorption of the char and regeneration of the char in fluid charcoal adsorption processes.

The hot combustion gases pass from the radiant heating section 44 over the top of the bridge wall 52 into the high velocity convection heating section 46 from whence the combustion gases pass outwardly through line 70 to a stack. The hot combustion gases are preferably passed through a waste heat boiler or suitable heat exchange device 71 for recovering some of the heat from these gases. Water or steam is passed through line 72 and waste heat boiler 71 to supply superheated steam under pressure which is supplied to manifold 62 by line 73 and passes into coking bed 22 or part of the superheated steam may be withdrawn through line 73' and used as fluidizing gas for the coking bed 22 as will be referred to presently. High velocity jets can be used in upflow legs 58 of the U-shaped tubes to give the desired attrition of coke particles and to control the particle size in the system, if necessary. This is applicable to all forms of the invention here disclosed.

As shown in the drawing the U-bend heat transfer tubes in the radiant heating section extend above and below the radiant heating section and the transfer tubes in the convection heating section extend below the floor 35 of the main furnace or below the level of the radiant heating section so that the points of connection are not exposed to the burner flames. As above stated coke is formed during the coking operation and finely divided coke particles are withdrawn from the dense fluidized bed 40 22 through line 74 to maintain the level 28 constant and are preferably cooled by quenching with water or other means and then recovered as such for use as fuel or for other uses.

An annular grid for steam distribution is arranged at 45 the bottom of the fluidized bed 22 in vessel 24 as shown at 76. The fluidized bed 22 is maintained as a dense fluidized highly turbulent bed by steam or other fluidizing gas introduced below the grid member 76 through line 77 and also by gas introduced into the upflowing legs 50 of the U-bend heat transfer tubes. The particles in the coking bed have a size of about 25 microns to 500 microns, preferably about 80-200 microns, and the superficial velocity of the gasiform material passing upwardly through the coking bed 22 is between about 0.3 and 5 55 feet per second.

Specific details for a commercial size fluid coker of the type disclosed in Fig. 1 will now be given. The hydrocarbon residuum feed selected has an API gravity of about 5° and a Conradson carbon of about 22 wt. percent. The gravity of the residual oil treated, however, may vary between about 10 and 20° API gravity and the Conradson may vary between about 5 and 35 wt. percent. The feed to the coking vessel also contains recycle oil from coking operation. The vaporous cracked products from coking zone 22 and the fresh residual oil feed are introduced into the bottom of the fractionator (not shown) of the recovery system and bottoms from the fractionator are used as feed for this specific example. The residual oil feed is thereby preheated and picks up residual coke particles as well as the heavy oil product which is to be recycled.

In the present case, about 23,000 barrels per operating day of residual oil plus 6,900 barrels per operating day of recycle stock or bottoms was heated to a temperature of about 755° F. and then passed through the heater 14

for raising the temperature of the oil feed to about 850° F.

The coking vessel 24 in this case has an inside diameter of about 14' 9" and a length of about 104 feet on the straight side. The coking vessel 24 is maintained at a temperature of about 850° F. and under about 15 lbs. per square inch gage pressure.

The fluidized bed 22 for this particular operation is about 89 feet deep and using coke as the inert fluidized particles has a density of about 30 lbs. per cubic foot. The coke particles have a size between about 80 and 200 microns. The superficial velocity of the steam plus vapors passing upwardly through the fluidized bed is about 3 feet per second.

The line corresponding to line 18 in Fig. 1 is an 8" line and in the design under discussion there are 12 connections from this arranged around the circumference of the vessel 24 to supply feed oil at a plurality of points. Steam under pressure is introduced through line 26 into each of these feed lines 18. About 1 to 5% by weight of steam on feed may be used.

The total vapor products going overhead through line 38 are as follows:

10.7 MM ³ SCF/SD	C ₃ -gas
230 B/SD	C ₄ H ₈
230 B/SD	C ₄ H ₁₀
4,370 B/SD	C ₅ -430° F.
6,320 B/SD	430-650° F.
8,620 B/SD	650-950° F.
6,900 B/SD	950° F. +

¹ Million standard cubic feet per stream day.

For the size coking vessel shown in Fig. 1, there are 21 U-bend transfer tubes (or 42 single tubes) arranged in a circle in the radiant heating section 44 of the fired furnace 42. The tubes have a diameter of 6" and a length of 17 feet within the radiant heating section 44, that is, that portion of the tubes between the top and bottom wall of the radiant heating section 44. The circle of the U-shaped heat transfer tubes 54 in the preferred arrangement above referred to has a diameter of about 13' 1". The size and number and arrangement of the tubes can be varied.

In the convection heating section 46 there are 44 single heat transfer tubes of 4" diameter formed from 22 U-bends with steam injection near the bottom of each U-bend. The heated length of the tubes in the convection heating section is about 17'.

Steam at about 850° F. and 50 lbs. per square inch gage in the amount of 20,000 lbs. per hour is passed to manifold 62 and is supplied to the upflow legs of each U-bend heat transfer tube. The furnace 42 is cylindrical and has a diameter of about 23 feet.

The radiant heating section is maintained at a temperature of about 2160° F. while the convection heating section 46 is maintained at a temperature of about 1330° F. The combustion gases passing to the stack through line 70 are at a temperature of about 900° F. About 880 tons per standard day of finely divided coke are removed via line 74 from fluid bed 22.

Referring now to Fig. 2 of the drawing, the reference character 102 designates a coking vessel provided with a fluidized bed of solids 104 having a level indicated at 106 with a dilute suspension or dilute phase 108 thereabove. A cyclone separator or other similar gas-solids separating device 112 is arranged in the upper portion of the coking vessel 102 for separating entrained solids from gasiform products going overhead, the solid being returned to the fluidized bed 104 through dip pipe 114 and the gasiform products passing overhead through line 116 to a suitable product recovery system.

Residual oil feed of the type above described heated to a temperature of about 800-950° F. is passed through line 120 and introduced through one or more lines 122

into the fluidized bed 104 in the coking vessel 102. In the commercial design unit twelve feed lines like line 122 are provided for supplying the preheated residual oil feed to the fluidized bed at a plurality of points around the circumference of the coking vessel.

In the form of the invention shown in Fig. 2 U-bend heat transfer tubes 124 hang from the bottom of the coking vessel 102 and have their upper ends in open communication with the bottom of the coking vessel so that finely divided solid particles from the fluidized bed 104 can be circulated down one leg 125 of the U-tube and up the other leg 125' of the U-tube and back into the fluidized bed. The U-shaped tubes are arranged in a heating vessel for supplying heat to the fluidized bed 104 in the coking vessel and for maintaining the temperature of the fluidized bed 104 between about 800° and 1400° F. and under a pressure of about atmospheric to 200 lbs. per sq. in. In the drawings only a few of the heat transfer tubes are shown but in a commercial unit having a construction such as shown in Fig. 2, there will be 332 such tubes having a diameter of 4 inches and connected to form 166 U-bends spaced about approximately 13" apart on equilateral triangles where the upper ends of the tubes connect into the bottom of the coking vessel 102. A steam line 126 is provided for injecting steam or other fluidized gas into the upflow leg of each of the heat transfer tubes 124, for causing circulation through the tubes.

The heat transfer tubes are arranged in a shell 128 provided with an internal insulation lining and in the commercial design the shell will have a diameter of about 13 feet and the insulation will be about 8" thick. The shell 128 is packed to about the level 132 with 1" diameter refractory spheres made of silica, alumina, carborundum, zirconia, etc. Instead of ceramic material, other materials such as metals may be used. In this form of coking apparatus the refractory spheres provide a fixed bed of heating material. For heating the heat transfer tubes during starting up, fuel gas is supplied through line 134 and air through line 136 to an auxiliary burner 138 and air heated to about 1500° F. then leaves the burner through line 142 and is passed to the duct 144 which extends into the center of the heating shell 128. At its inner end the duct 144 connects into a 30" diameter axial distributor 146 which comprises a hollow cylindrical tube extending from the exterior of the bottom of coking vessel 102 to the bottom of shell 128, the tube being perforated to permit the passage of gas.

After the vessel 128 is heated up the flow of fuel gas and air through burner 138 is stopped but air continues to flow to axial distributor 146. Fuel gas is then introduced into the stationary packing 133 in shell 128 through a plurality of perforated pipes or tubes 148 arranged in the packing in one or more circles substantially concentric with said distributor 146. By arranging the tubes in this way overheating is avoided. If all the fuel were added to the entire air stream in the packed bed heater 128 the combustion would give theoretical flame temperatures of roughly 3600° F. which would give exceedingly high heat transfer rates.

However, in many cases there is the possibility of the heat transfer tubes becoming plugged on the inside and with flame temperatures of 3600° F. a plugged tube would immediately result in tube failure since the metal would heat up approaching flame temperatures. This would cause a shutdown of the plant and in order to avoid this possibility it is advisable to limit the flame temperature around the tubes to 1500° F. This is done by spaced fuel injection by the perforated tubes 148. That is, the fuel is added in increments to the total air stream. The air from distributor 146 flows radially outward through the packed bed 133 surrounding the U-shaped heat exchange tubes 124. Thus, for example, when the gas containing air flowing across the tubes has cooled to say 1400° F. enough fuel gas is added to raise the temperature of the

gas to about 1600° F. This incremental addition of the fuel gas is effected by the perforated pipes 148. Thermocouples are provided to facilitate this control. To prevent coking of the fuel the perforated or porous tubes may be insulated. For example, one-half inch of insulation on the outside of the tubes will prevent excessive temperatures on the fuel gas passing therethrough.

As shown in Fig. 2 of the drawings, the air from the distributor 146 flows radially outward from the openings in the distributor and through the packed bed 133 and in this way also provides increased contact time just before the gases leave the packing whereby complete combustion of the fuel gas is assured.

The packed bed 133 may be made up of refractory material such as silica, alumina, carborundum, zirconia, etc., or metals or other material and should preferably be porous with a high surface area to promote combustion. If desired, a combustion catalyst may be used in connection with the refractory packing.

In a commercial design unit of the modification shown in Fig. 2 of the drawings, the U-tubes 124 have a height of about 28 feet. There are 100 equally spaced one-inch perforated pipes 148 for this design. The packed bed 133 is maintained at a temperature of about 1500° F. and under a pressure of about one pound per square inch gage.

Coke produced in the form of finely divided particles is withdrawn from the fluidized bed 104 through line 152 and may be cooled or quenched and then stored or used as such.

The hot combustion gases leaving the heating shell 128 pass upwardly through line 154 through waste heat boiler 156 and then through water preheater 158 before passing to the stack through line 162. After passing through the waste heat boiler 156 the combustion gases are at a temperature of about 600° F. and after leaving the preheater 158 the gases are at about a temperature of about 300° F.

In the commercial design such as shown in Fig. 2 the twelve feed lines 122 have a diameter of about 3" for supplying the oil feed at about 870° F. to the coking vessel 102. The oil feed comprises 23,000 barrels per operating day of reduced crude having an API gravity of 5 to 10° and a Conradson carbon of about 20 weight per cent and an initial boiling point of about 1100° F. The oil feed also includes 6240 barrels per operating day of recycle oil from the process.

The fluidized bed of coke 104 in the coking vessel 102 is about 20 feet deep and has a density of about 30 lbs. per cubic foot where the coke particles have a size between about 20 and 400 microns. The coking vessel 102 has an inside diameter of about 11.5 feet and a straight side of about 35 feet. The coking fluidized bed 104 is maintained at a temperature of about 1100° F. and under a superatmospheric pressure of about 110 lbs. per sq. in. gage.

Instead of passing the air through axial distributor 146, it may be introduced below a distribution grid member (not shown) arranged at the lower portion of the heating shell 128 to support the bed 133 and the air distributed across the area of the heating shell in this way. The rate of flow of solids through U-bend tubes 124 may be the same as that in U-bend tubes 54 described above in connection with Fig. 1.

The technique of supplying heat to a fluid bed by circulation of solids through hot U-bend tubes is especially valuable when the solids are to be heated under pressure. At low pressure the solids can often be heated by direct contact with hot flue gas. At high pressure, however, the air compression cost for burning is prohibitive. By coking at relatively high pressures, it is unnecessary to compress the product gas for light ends recovery.

Referring now to Fig. 3 of the drawings, the reference character 180 designates a coking vessel provided with a separating means such as a cyclone separator 182

having a dip leg 184 and a product outlet gas line 186. The coking vessel 180 has a fluidized bed of solids 188 therein having a level indicated at 192 and a dilute phase or dilute suspension 194 thereabove. Residual hydrocarbon oil as above described which is to be treated is passed through line 196 by pump 198 through heater 200 and the heated oil is introduced through line 201 into the fluidized bed of solids 188 maintained at a coking temperature between about 800° and 1400° F. in the coking vessel 180. Coking vessel 180 may be maintained at a pressure between about 0 and 200 lbs. per sq. in. Steam is preferably added to the heated oil through line 202. While one line 201 is shown for feeding the heated oil to the coking vessel 180, in the large commercial design it is preferred to have 12 such lines feeding the oil into the fluid bed in a plurality of places. Coke is formed during the coking process and fluidized coke product is removed from the fluidized bed 188 through line 204 and may be treated as hereinbefore described in connection with other forms of the invention.

In the form of the invention shown in Fig. 3 the U-bend heat transfer tubes are heated by being submerged in a fluidized bed of inert solids, the solids being removed from the bed, heated and returned to the fluidized heating bed. Surrounding a portion of the lower end of the coking vessel 180 is a heating vessel 206 having an enlarged upper portion or dome 208. A dense bed of highly turbulent inert solids of about 50-200 mesh is located in the vessel 206 as shown at 212 having a level at 214. The inert solids may be made of metallic material such as iron spheres but silica gel or other similar materials such as carborundum, clay, alumina, silica, etc. are preferred.

U-bend heat transfer tubes 214 are provided having a down flow leg 216 and an upflow leg 218 which hang from the bottom of coking vessel 180. The upper ends of the U-tube open into the bottom portion of the dense bed 188 in coking vessel 180. Steam or other fluidizing gas is introduced into the lower portion of the upflow leg 218 of the U-bend by line 220 for causing circulation of the solids through the U-bend heat transfer tube. Steam from upflow legs 218 is used to fluidize coking bed 188. The superficial fluidizing gas velocity is between about 0.1 and 5 ft. per second in fluid bed 188. While only a few of the U-bend tubes are shown in the drawing, it is to be understood that in a commercial design unit where about 30,000 barrels of oil are processed per operating day in the coking vessel that there will be about 166 U-bend tubes of 4" diameter made up of 332 single tubes. The centers of the connections of the U-tubes with the bottom of the coking vessel 180 will preferably be spaced about 13" apart on equilateral triangles. The length of each tube of the U-tube heat transfer construction will be about 12 feet.

Some fuel gas or other fuel is introduced through manifold 222 to lines 224 which feed the fuel gas into the bottom of the fluidized bed 212 in the heating vessel 206. Similarly some air is introduced through manifold 226 and lines 228 into bottom portion of the fluidized solids bed 212 in the heating vessel 206. The burning of the fuel in the fluidized solids bed 212 maintains the temperature of the fluidized bed between about 1000° F. and 2000° F. preferably at about 1500° F. Also the gases as they pass upwardly through the bed 212 maintain it in a fluidized dense and highly turbulent condition. The superficial velocity of the gas passing upwardly through the fluidized bed 212 is 5 feet per second and may be varied between 1 foot per second and 10 feet per second. Additional fuel and air to supply heat to the inert particles of the fluidized bed 212 is utilized outside heating vessel 206 as will be hereinafter described.

As the gases pass upwardly into the enlarged dome 208 their velocity is decreased and some of the particles entrained by the gases are dropped back into the fluidized bed 212. Additional air is added near the top of the

fluidized bed 212 through one or more lines 230 to control the solids circulation rate. Thus a higher air rate will increase the entrainment and increase the solids circulation.

Near the top of the heating vessel 206 and leading from the enlarged dome 208 is a line 232 for carrying solids from the heating vessel 206 in suspension. These solids are heated and then returned to the heating vessel 206. For heating these solids at starting up only a burner 234 is provided into which air is introduced at 236 and fuel at 238, the fuel preferably being a gas. The gas and air are introduced into the upper portion of the burner 234 and in burning raise the temperature of the gas to about 1500° F. After the unit is heated up, flow of gas through line 238 may be turned off and fuel gas passed through line 242 into transfer line heater 246. When the auxiliary burner is in use, the hot gases from line 244 and the suspended solids in line 232 are mixed and the mixture passed through the upflow heater 246 for heating the suspended solids to a temperature between about 1000° F. and 2000° F., preferably about 1600° F. In the transfer line heater 246 the mixture is maintained in a highly turbulent condition and extremely good contact and heating are obtained. The suspension is then introduced into a solids-gas separating means such as a cyclone separator 248 for separating the heated solids from the hot gases and the heated solids at a temperature between about 1000° F. and 2000° F., preferably about 1600° F. are passed through standpipe 252 provided with a control valve 254 to the lower portion of the fluidized bed 212 in the heating vessel 206.

The hot gases separated in the separator 248 pass overhead through line 256 and are passed to waste heat boiler 258 and water preheater 262 before being passed to the stack at about 300° F.

In a commercial unit it is preferred to use three sets of equipment including the upflow heater 246, cyclone separator 248 and standpipe 252 and associated parts to avoid the use of oversized equipment. A single starting up burner 234 is used but the outlet from this burner will be divided into three parts with each part going to an upflow heater similar to 246. The outlet from the standpipe 252 may be at one point or each of the three sets of equipment above referred to may have a single standpipe associated with it for delivering the hot solids to three different bottom portions of the heating vessel 206, preferably equally spaced to promote uniform flow distribution.

In a commercial design unit the twelve feed connections 201 will be 3" diameter pipes and the coking bed 188 will be maintained at a temperature of about 1100° F. and under a superatmospheric pressure of about 110 lbs. p. s. i. g. The fluidized bed 188 will be about 20 feet deep and using coke particles having a size of 20 to 400 microns the density will be about 30 lbs. per cubic ft. The coking vessel has an internal diameter of about 11.5 feet and will be 35 feet on the straight side. The superficial velocity flowing up through the coking bed will be about 3 ft./sec.

The enlarged dome will have an internal diameter of about 15.5 feet and a straight side of about 3 feet. The air connections 230 will be about 4" in diameter and there will be six of these connections. The air connections 228 at the bottom of the heating bed will be 6 inches in diameter and there will be 12 of these air connections.

The auxiliary burner will have an outlet of 46" internal diameter. Line 244 will have an internal diameter of about 30". The upflow vertical heating element 246 for heating the suspension will be about 15 ft. long and will have an internal diameter of about 54 inches. Three cyclone separators will preferably be used, one for each set of equipment above referred to. Standpipe 252 will have an internal diameter of about 18".

From the above description of Fig. 3 it will be seen that part of the air and fuel gas are added to the heat transfer bed 212 in heating vessel 206 to provide good fluidization of the solids and provide efficient heat transfer. It is

impractical to put all the combustion air into the fluidized bed 212 and therefore most of the burning for supplying the heat is carried out outside the bed 212 in upflow heating vertical tubular member 246. If all the air were added to the bed, the velocity of the air would be too high to give adequate bed density for good heat transfer in the heating vessel 206.

To increase the circulation of solids through bed 212 more air is added near the top of the heat transfer bed 212 as at 230 whereby more solids are carried off from the bed 212 in suspension without otherwise affecting conditions in the heat transfer bed 212. The superficial velocity of the combustion gases passing upwardly through vertical heater 246 is between about 10 and 60 ft./sec., preferably about 20-30 ft./sec.

One or two stages of cyclone separators may be used wherever they are used in the designs above described.

Heat transfer may be improved by using baffles or stationary packing in the fluidized heating bed 212 to give a temperature gradient from the bottom to the top of the bed thereby improving the temperature differential for heat transfer at constant heating solids removal temperature.

The coke holdup in the coking zones corresponds to about 7.9 weight of oil per hour per weight of coke based on total feed but may be varied between about 1 and 10 w./hr./w. when using high temperatures. For lower temperatures the w./hr./w. may be between about 0.1 and 3.

The amount of heat input can be controlled by regulating the amount of fuel added to the external heater 246. Also heat transfer in the fluidized heating bed 212 can be changed independently by adjusting the air rate introduced into the bed 212 through lines 228. At very low velocity, fluidization and heat transfer are poor but as the velocity of the upflowing gas is increased heat transfer first improves sharply and then decreases gradually and finally falls off sharply as bed density is lost.

The rate of circulation of solids through the external heating zone 246 may be controlled by changing the amount of air introduced at the top of the bed 212 through lines 230. The entrainment of the solids in the line 232 leaving the heating vessel 206 depends on the total air flow and this can be varied without changing conditions in the fluidized bed 212.

Instead of using the U-tube shaped sections, other forms may be used as for example, a tubular member may be divided by a vertical partition stopping above the bottom of the tubular member so that the solids can go down the tubular member on one side of the partition and up the tubular member on the other side of the partition, thus in effect constituting one form of U-tube. Or concentric tubes or pipes may be used for similar U-tube type flow in which the solids go down through the central tube and up through the outer tube or vice versa.

What is claimed is:

1. In a process wherein high boiling residual petroleum hydrocarbons which contain constituents unvaporizable at ordinary pressures without cracking are converted into lower boiling hydrocarbons in contact with a dense fluidized bed of finely divided coke maintained at a coking temperature of about 800 to 1400° F. in a coking zone and wherein vapors of said lower boiling hydrocarbons are removed overhead from said coking zone while coke product is withdrawn from the dense bed, the improvement in supplying heat to said coking zone which comprises downwardly withdrawing a multiplicity of individual confined narrow streams of said finely divided coke in dense phase from the bottom of said bed, circulating each withdrawn stream along a U-shaped confined path back into a bottom portion of said bed, injecting an inert gas into the bottom portion of the upflow leg of each said U-shaped paths to control the circulation rate of the coke, maintaining said coke in said confined U-shaped paths within a heating zone in indirect heat exchange relation with another dense bed of finely divided solid heat carrier

particles having a disperse phase of heat carrier particles and gas thereabove, passing a fluidizing gas upwardly through the last-named dense bed at a superficial velocity of less than about 10 ft./sec., said heating zone being arranged beneath said coking zone and being maintained at a temperature above said coking temperature and within the range of about 1000 to 1500° F. and at substantially atmospheric pressure, continuously withdrawing a portion of said disperse phase containing heat carrier particles from an upper portion of said heating zone, heating the withdrawn disperse phase to a temperature not in excess of 2000° F. by mixing it in a confined elongated burner zone with hot gases at a superficial gas velocity of about 10 to 60 ft./sec., separating hot heat carrier solids from said disperse phase, and returning said hot separated solids to said dense bed in the heating zone.

2. A process according to claim 1 wherein said hot gases in the burner zone contain combustible fuel and wherein an oxygen-containing gas is added to the upper portion of the heating zone so as to regulate entrainment of heat carrier solids from the dense bed of the heating zone to the elongated burner zone.

3. A process according to claim 2 wherein the fluidizing gas passing upwardly through the dense bed of the heating zone contains a burning mixture of hydrocarbon fuel and air and wherein the heat transfer coefficient to the U-shaped streams is regulated by adjusting the velocity of said fluidizing gas in said dense bed of the heating zone.

4. A process according to claim 2 wherein the coking zone is maintained at an elevated pressure up to about 200 lbs. per sq. in. and at a temperature of about 1100 to 1400° F. and the heating zone is maintained at substantially atmospheric pressure and at a temperature higher than said coking zone temperature.

5. A process according to claim 1 wherein the fluidizing gas passing upwardly through the dense bed of the heating zone contains a burning mixture of combustible fuel and oxygen-containing gas.

6. An apparatus for the conversion of hydrocarbons including in combination a coking vessel adapted to contain a fluidized bed of inert solids, means for introducing

oil to be converted into said coking vessel, means for removing vaporized reaction products and coked particles from said vessel, U-shaped tubes hanging from the lower end of said vessel with the upper ends of the U-shaped tubes in communication with the lower portion of said vessel whereby solid particles from said vessel may be circulated down through one leg and up through another leg of each U-shaped tube, means for introducing a gas into the upflow leg of each U-tube to assist in the circulation of solids, a heating chamber surrounding said U-shaped tubes including the lowermost portions thereof, said heating chamber being adapted to contain a dense fluidized bed of inert solid particles superimposed by a dilute suspension of solids, means for introducing fuel and air into a lower portion of said heating chamber for burning therein and for supplying fluidizing gas for said bed, an outlet line at the upper portion of said heating chamber for removing combustion gases and entrained solids therefrom, separating means associated with said outlet line for separating entrained solids from gases and pipe means for returning separated solids from said separating means to a lower portion of said heating chamber, means for introducing a controlled amount of gas into the upper portion of said heating chamber for regulating the entrainment from the fluidized bed and thereby regulating the circulation of solids through said outlet line, and pipe means for introducing fuel into said outlet line for supplying additional heat to the circulating solids.
